MANUALLY OPERATED FLUID APPLICATOR

Charles E. Vanasse, New York, N. Y.

Application November 18, 1949, Serial No. 128,093

3 Claims. (Cl. 15—132.5)

1

This invention relates to manually operated fluid applicators of the general type incorporating a fountain roll provided with a handle. The operator fills the fountain roll with fluid such as paint and the like and then using the handle rolls the fluid onto the surface to which it is desired to apply the fluid. Devices of this character are particularly adapted for painting walls and the like.

One of the objects of this invention is to provide a device of the character described which permits the user to control the amount of fluid rolled onto the work from the fountain roll. Another object is to provide a device of this character which is constructed in a simple and inexpensive manner to provide a reliable device permitting the application to the surface of the precise amount of fluid desired. Other objects may be inferred from the following.

A specific example of a device constructed in accordance with the invention is illustrated by the accompanying drawings and described hereinbelow for the purpose of disclosing the principles and operation of the invention. Once these principles and operation are understood those skilled in the art may incorporate them in forms other than are involved by the specific example which is illustrated and described herein.

In the accompanying drawings:

Fig. 1 is a side view showing the device in operation;

Fig. 2 is a top view of the device;

Fig. 3 is a horizontal section of a detail of the device taken on the line 3—3 in Fig. 1; and

Fig. 4 is a horizontal section of a detail of the device taken on the line 4—4 in Fig. 1.

The illustrated device is a manually operated fluid applicator including in combination a fountain roll 11 and a transfer roll 12. The transfer roll 12 is longer than the fountain roll 11. An elongated loop of heavy gauge wire provides straight cantilever arms 13 and 14 proportioned to be spanned by the operator's hand as illustrated by Figs. 1 and 2 with the rolls 11 and 12 respectively mounted rotatively on the swinging ends of these arms 13 and 14. This proportioning is effected by making the bend 15 of the wire loop with an adequately short radius.

A second elongated loop of heavy gauge wire is fastened substantially parallel to the above-mentioned loop.

This second loop includes a short arm forming a cantilever beam 16 extending substantially parallel to the arm 14 from the bend 17 of this second loop, and a longer cantilever arm 18 ex-

tending along the arm 13 of the first loop and which is of substantially the same length as this arm 13. The two loops are fastened together by two rivets 19 adjacent their bends 15 and 17 respectively and adjacent these bends' junctions with their respective straight portions. The fastenings are arranged to leave the arm 14 and beam 16 relatively free from each other, while the arms 13 and 18 work as a single arm.

The first-mentioned wire loop has its arm 14 rectangularly bent at its swinging end to form a rectangular loop 20 providing a right angular cantilever shaft 21 mounting the transfer roll 12 in a rotative manner. The swinging ends of the arms 13 and 18 that work together are also rectangularly bent in opposite directions to provide rectangular loops 21' and 22 respectively providing oppositely pointing ends 23 and 24 which rotatively mount the fountain roll 11. The two rolls are mounted parallel to each other.

As shown by Fig. 3 the fountain roll 11 is in the form of a perforated sheet or screen drum 25 having fluid impervious drum heads 26 retained at this drum's ends by a tension tube 27 provided with externally threaded ends 28 which pass through holes in the drum head 26 and are externally thereof provided with nuts 29. At one end of the drum an internal nut 30 is provided so that at that end the drum head and the tube 27 are formed into a unit.

Loading of the drum 11 with the fluid is accomplished by removing the nut 29 at the opposite end from the nut 30 and removing the drum head 26 at that end. Replacement of the drum head and nut recloses the fountain roll.

The oppositely projecting ends 23 and 24 of the cantilever arms 13 and 18 fit into the ends of the tension tube 27 and are prevented by cotter pins 31 from entering these ends too far for easy rolling action of the drum 11. The two rectangular loops 21 and 22 are shaped so they spring together to retain the tension tube 27 between them, the use of force serving to spring these loops 21 and 22 apart to disengage their ends 23 and 24 from the ends of the tension tube 27.

The transfer roll 12 includes a solid cylindrical body 32 having a hole through which the cantilever shaft 21 passes, the free end of the latter being externally threaded and provided with a retaining nut 33 and its opposite ends having a cotter pin 34 working against a thrust washer 35 to keep the body 32 from going inwardly. The nut 33 prevents opposite motion of the cylinder 32, the latter being free to rotate on the shaft 21.

As shown by the drawings the transfer roll 12 is considerably smaller than the fountain roll 11. The drum 25 of the fountain roll is covered with a fluid pervious and absorbent covering 36, while the body 32 of the transfer roll has a fluid absorbent covering 37. Both the coverings 36 and 37 may comprise a relatively thick layer of felt when the fluid handled is in the nature of paint or other liquid.

The cantilever beam 16 of the secondly mentioned loop has an end 38 curving towards the cantilever arms 13 and 18. The tip of this end 38 has a hole through which one end of a wire loop arrangement is passed. This wire loop arrangement is made of stiff wire bent to provide a pivot shaft 39 passing through the hole in the tip of the end 38. From this pivot shaft the wire loop arrangement extends to provide a straight shifting strut 40 which bears against the cantilever arm 14 by way of a right angular portion 41. The wire loop arrangement then extends from this portion 41 downwardly at an angle to form a trigger 42 angularly arranged respecting the various arms of the device at a position accessible to the fingers of the operator's hand when spanning the respective arms as shown by Fig. 1.

In operation paint or other fluid is first loaded in the fountain roll in the manner previously described. This fountain roll is then positioned between the oppositely extending ends 23 and 24 of the rectangular loop portions 21 and 22. Then the operator grasps the respective cantilever arms as shown by Fig. 1. The transfer roll 12 is positioned against the surface to which the fluid is to be applied and the device is rolled along it while the operator squeezes the respective cantilever arms together. The bends 15 and 17 of the two elongated loops of heavy gauge wire function together as a spring which normally keeps the arm 14 biased away from the arms 13 and 18. In the event this spring action is insufficient or deterioriates with age, the operator uses his fingers to pull up on the trigger 42 which then pulls the shifting strut 40 between the end 38 of the cantilever beam 16 and the cantilever arm 14 and thus wedges the latter arm downwardly with consequent separation of the transfer roll from the fountain roll.

With the device controlled in the above manner the paint or other fluid permeates the covering 36 of the fountain roll 11 and is absorbed thereby. In turn the covering 37 of the transfer roll 12 absorbs more or less of the paint or other fluid from the covering 36 and the amount absorbed is transferred to the surface to be painted or otherwise treated with the fluid. The covering 36 is always saturated but the saturation of the covering 37 of the transfer roll is completely under the control of the operator. The operator merely squeezes the handle provided by the cantilever arms of the elongated loops more tightly together or lets up on the force while pulling on the trigger 42 if necessary, all as required to respectively get a heavier or a lighter transfer of the fluid from the fountain roll to the surface to which the fluid is being applied.

Although the wire loop arrangement forming the shifting strut and trigger is made from lighter gauge wire than are the elongated loops providing the arm 14 and the beam 16, these heavier parts are flexed elastically apart by the shifting strut 40 because so much of the stress in the latter is carried in compression and because the force is applied to the parts 14 and 16 in the form of beam flexure stress.

As shown by dotted lines in Fig. 2 the user may flex the cantilever arm 14 laterally respecting the other cantilever arms 13 and 18. This is done by manipulation of the arm 14 with the fingers of the hand grasping the device. This lateral flexing longitudinally projects the free end of the transfer roll 12 flush with or beyond the arm 22 and permits the use of the transfer roll clear up to and in the corners of right angular surfaces. Thus the device can apply fluid such as paint on the walls of a room clear up to and in the corners formed by adjacent right angular walls. The two arm portions 21 and 22 therefore may be used to support the naturally heavy fountain roll 11 without interfering with the use of the device in corners or other close places.

I claim:

1. A manually operated fluid applicator including in combination a fountain roll, a transfer roll, and a handle mounting said rolls parallel, said handle including an elongated loop having cantilever arms proportioned to be spanned by the operator's hand and with said rolls respectively mounted rotatively on the swinging ends of said arms, said arms being yieldable to permit movement of said rolls toward and away from each other, one of said arms being provided with a cantilever beam extending therealong from the bend of said loop, and a pivoted strut provided with a manually operable trigger coacting with one of said arms and said beam with its said trigger angularly arranged respecting said arms at a position accessible to the fingers of the operator's hand when spanning said arms, whereby the relative positions of said rolls may be controlled.

2. A manually operated fluid applicator including in combination a fountain roll, a transfer roll, and a handle mounting said rolls parallel, said handle including an elongated loop having cantilever arms proportioned to be spanned by the operator's hand and with said rolls respectively mounted rotatively on the swinging ends of said arms, said arms being yieldable to permit movement of said rolls toward and away from each other, one of said arms being provided with a cantilever beam extending therealong from the bend of said loop, and a pivoted strut provided with a manually operable trigger coacting with one of said arms and said beam with its said trigger angularly arranged respecting said arms at a position accessible to the fingers of the operator's hand when spanning said arms, whereby the relative positions of said rolls may be controlled, said beam comprising a shorter arm of a second elongated loop fastened to the first-named loop and having a longer arm extending along the arm of the first-named loop mounting said fountain roll with the last two named arms respectively mounting said fountain roll by the latter's opposite ends.

3. A manually operated fluid applicator including in combination a fountain roll, a transfer roll, and a handle mounting said rolls parallel, said handle including an elongated loop having cantilever arms proportioned to be spanned by the operator's hand and with said rolls respectively mounted rotatively on the swinging ends of said arms, said arms being resilient to permit movement of said rolls toward and away from each other, one of said arms being provided with a cantilever beam extending therealong from the bend of said loop, and a pivoted strut provided with a manually operable trigger coacting with one of said arms and said beam with its said trigger angularly arranged respecting said arms at a position accessible to the fingers of the operator's

hand when spanning said arms, whereby the relative positions of said rolls may be controlled, said beam comprising a shorter arm of a second elongated loop fastened to the first-named loop and having a longer arm extending along the arm of the first-named loop mounting said fountain roll with the last two named arms respectively mounting said fountain roll by the latter's opposite ends, said fountain roll including a perforated drum container constructed to be filled with the fluid and having a covering that is fluid permeable and absorbent, and said transfer roll including a roll body substantially smaller in diameter than said drum container and of at least the same length as the latter and having a covering 15 that is fluid absorbent.
